CLAIM

The ornamental design for a flashlight, as shown and described.

DESCRIPTION

FIG. 1 is a front view of a flashlight showing my new design; FIG. 2 is a rear view thereof; FIG. 3 is a left-hand-side view thereof; FIG. 4 is a right-hand-side view thereof; FIG. 5 is a top view thereof; FIG. 6 is a bottom view thereof; and, FIG. 7 is a perspective thereof.

The broken lines shown in the drawings depict portions of the flashlight that form no part of the claimed design.
